ERNST LÜCKE, OF BERLIN-SIEMENSSTADT, GERMANY, ASSIGNOR TO SIEMENS & HALSKE, AKTIENGESELLSCHAFT, OF SIEMENSSTADT, NEAR BERLIN, GERMANY, A CORPORATION OF GERMANY

THERMIONIC TUBE

Application filed February 19, 1927, Serial No. 169,431, and in Germany February 26, 1928.

This invention relates to a thermionic tube and more particularly to a tube using an arc as a source of electrons.

Discharge tubes for the amplification of electrical currents and the production of electrical oscillations are known in which the incandescent filament is replaced by a spontaneous or unassisted arc discharge. In these devices, one disturbing element is that the current flowing across the arc is not constant, with the result that current surges or rushes (impulses) are superposed upon the arc current, and these may be of such a value that the use of the arc as an electron source for many purposes becomes questionable.

It is an object of this invention to avoid variations in the strength of the arc current. According to the present invention, a distinct electron source is provided above the filament of the arc discharge. For this purpose, for instance, one or more heated electrodes may be disposed above the surface of the main cathode, or else one or more discharges (arcs) may be maintained. Another scheme would be to use the cathode itself as a base for the auxiliary arcs.

The accompanying drawing shows two embodiments of the basic idea of the invention by way of example.

Figure 1 is a section through a tube utilizing a mercury arc, having an auxiliary cathode of the filament type, and

Figure 2 is a section through a similar tube with another type of auxiliary cathode.

Referring to the embodiment shown in Figure 1, 1 is the main cathode, 2 the main anode, 3 the control grid, and 4 the amplifier anode. In order to insure as great as possible a constancy of the arc current flowing between cathode 1 and anode 2, a hot filament 6 supplied from battery 5 is disposed above the cathode surface. Of course, in lieu of only one hot filament, a plurality thereof could be provided, and these should then be uniformly distributed around the periphery of the tube. 7 is a screen which is designed to prevent precipitation or condensation of droplets of mercury upon the filament 6. To insure abundant electron emission from filament 6, the same in well known manner may

be coated with a film of oxide or thorium. Under certain circumstances, it may also be suitable to use filaments coated with hydrides of alkaline earths.

Figure 2 shows another embodiment of the invention. 8 is a discharge vessel, 9 the main cathode, 10 the main anode, 11 the control grid, and 12 the amplifier anode. In the middle of cathode 9 is secured a pin 13 which is made of zirconium or hafnium oxide. But it may also have the composition of and be made like the glowers used in Nernst lamps. The top part of said pin 13 may be electrically heated by heater spiral 14. If by the aid of the spiral 14 the end of the pin 13 is caused to incandesce, then an arc will be set up in the direct neighborhood of the pin, emission being automatically regulated by its own current. The end of pin 13 may be coated with oxides of alkaline metals, hydrides of alkaline earth metals, and the like.

The operation of the device as here disclosed is probably predicated upon the fact that the electrons or ions issuing from the hot filament or at the auxiliary discharge partly compensate the space-charge at the cathode, or upon the fact that the same diminish the requisite energy expenditure normally covered or supplied by the arc discharge by causing the detachment of electrons from the cathode.

Having thus described my invention, what I claim is:

1. In an electron discharge device, an anode, an auxiliary anode, a grid, a primary cathode consisting of liquid mercury, and a secondary cathode, said secondary cathode comprising a pin of electron-emissive material extending through and above the primary cathode, and a heating coil within said pin.

2. In an electron discharge device, a primary anode, a secondary anode, a grid, a primary cathode comprising liquid mercury, and a secondary cathode comprising an oxide pin of electron-emissive material extending through and above the liquid mercury, and a heating coil within the pin to cause the said pin to incandesce.

ERNST LÜCKE. 100
